UNITED STATES PATENT OFFICE.

ISAAC C. SQUIER, OF NORTH PLAINFIELD, NEW JERSEY.

INKING MECHANISM FOR PRINTING PRESSES.

Application filed February 14, 1922. Serial No. 536,419.

To all whom it may concern:

Be it known that I, ISAAC C. SQUIER, a citizen of the United States, residing at 16 Grandview Ave., North Plainfield, in the county of Somerset and State of New Jersey, have invented certain new and useful Improvements in Inking Mechanism for Printing Presses; and I hereby declare that the following is a full, clear, and exact description thereof, reference being had to the accompanying drawings, which form part of this specification.

This invention has particular relation to inking mechanism for printing presses, and the like, and is especially designed for use in connection with rotary web presses, but is adaptable to all types of printing presses and other machines wherein uniform distribution of ink or color on the distributing surface is desired.

The object of the invention is to thoroughly disseminate and uniformly distribute the ink on the distributing surface, whether it be cylindric or flat, and to do away with the ordinary vibrators or distributor rolls; and the present invention consists broadly in distributing ink upon such surface by means of ink distributing members, preferably disks or rubbing devices which operate upon the distributing surface to distribute the ink thereon; said distributing members as I shall hereinafter term them preferably being arranged to rotate on axes approximately perpendicular to the distributing surface.

In the accompanying drawings I have illustrated one practical embodiment of the invention which I will describe in detail to enable others skilled in the art to understand and use the same, but the invention is not restricted to the particular embodiment thereof illustrated in the drawings and I refer to the claims for summaries of the essentials of the invention and novel features of construction and novel combinations of parts for which I desire protection.

In said drawings Fig. 1 is a diagrammatical sectional elevation of an inking apparatus embodying the invention. Fig. 2 is a diagrammatical detail view on the line 2-2, Fig. 1, showing the arrangement of the disks relative to the drum. Fig. 3 is a detail view partly in section on the line 3-3, Fig. 1. Fig. 4 is a detail diagrammatical sectional view on the line 4-4, Fig. 1.

Hereinafter in the description I will refer

to the distributing surface upon which the ink is to be distributed as a drum, but this surface may be an ordinary inking drum, such as is commonly used in printing presses, or any other form of surface, curved or flat, upon which the ink is to be distributed. I will also refer to the ink distributing members as disks, meaning thereby to include any kind of rubbing devices which operate to distribute the ink on such distributing surface, and preferably rotate on axes perpendicular to the surface on which the ink is to be distributed.

The drum 1 may be of any desired type, and ink might be supplied to the surface of this drum by any preferred means. In the example shown the drum may be supplied with ink from an ordinary fountain F by means of a ductor D in the well known manner. The ink may be transferred from the surface of the drum 1 to the printing surface by any suitable means, and in accordance with the construction of the press or machine to which the invention is applied. In the example shown form rollers R transfer ink from the surface of the drum 1 to a plate cylinder P.

Arranged beside drum 1 and cooperating with the surface thereof is a plurality of series of ink distributing disks 2 which extend longitudinally of the drum. The disks in one series alternate with the disks in the adjacent series. Preferably these disks are set at a tangent to the drum, and are preferably mounted to rotate on axes approximately perpendicular to the distributing surface and to the axis of the drum.

As shown each disk 2 may comprise an annular distributing portion 2^a secured to the face of a circular head 2^b on the spindle 2^c; portion 2^a being preferably clamped against the head 2^b by means of a bevel nut 2^d engaging a threaded part 2^e of the spindle which projects beyond the head as shown. This permits the portion 2^a to be readily renewed when it becomes worn. Portion 2^a should be of a suitable material adapted to distribute the ink on the surface of the drum 1 where it contacts therewith, and to have slightly yielding or rubbing contact with the surface of the drum. The distributing disks are set at such an angle or tangent to the drum that only part of the portion 2^a of the disk contacts with the surface of the drum 1, as shown in Fig. 2.

As shown in Fig. 2, only so much of the

face of each portion 2^a (of the upper series of disks) as lies between the points *a*—*b* contacts with the periphery of the drum 1; while so much of the face of the portions 2^a 5 of the lower series of disks, (which alternate with the disks in the upper series) as lie between the points *a*—*b* contact with the periphery of the disk; and, as indicated in Fig. 2, the portions of the drum not contacted by the upper series of disks 2 is 10 contacted by the lower series of disks, so that the entire surface of the drum will be actually operated upon by the disks in both series. I have only shown two series of 15 disks but, if desired, three or more series could be used to enhance the distribution.

In the example shown the spindles 2^c are journaled in suitable bearing brackets 3, 3^a, which may be fastened to any suitable support on or in the main frame of the press; the particular means of support being immaterial. Upon each spindle 2^c intermediate the supports is a worm gear 4 which meshes with a worm gear roll 5 extending longitudinally of the series of distributing disks, intermediate the upper and lower sets of worm gears 4, as indicated in Figs. 1 and 4, and adapted to simultaneously operate all of the gears.

39 The roll gear 5 may be driven by any suitable means, not shown, so as to impart any desired speed of rotation to the distributing disks 2. The inking drum 1 may also be driven by any desired means, not shown, so as to cause it to rotate; such driving means form no part of the present invention, and will be readily supplied by a mechanic, and therefore are not illustrated herein.

40 The invention is not restricted to a worm gear drive for the disks 2, nor to the particular arrangement of supports for said disks as shown in the drawings.

The disks 2 may be yieldingly pressed 45 against the periphery of roll 1 in any suitable manner. In the example shown the rear ends of spindles 2^c are reduced in diameter (see Fig. 1) and a helical spring 6 is placed in the bearing 3^a and interposed 50 between a bushing 7, screwed into the outer end of 3^a, and a shoulder 2^f on the spindle 2^c. By adjusting this bushing the tension of the spring 6 can be regulated so that it will act to yieldingly hold the disk 2 against the 55 drum 1 with any desired degree of pressure.

Operation.

If the drum 1 is rotated in the direction 60 of the arrow as shown in Fig. 1, the ink supplied thereto from the fountain F, will be distributed on the surface of the drum by the action of the disks 2, which rotate approximately at right angles to the axis of 65 the drum and distribute the ink not only

circumferentially but longitudinally of the drum, and by reason of the plurality of series of these distributing disks the ink is thoroughly disseminated over the entire surface of the drum.

70

I have shown but two series of distributing disks, but if a finer or more uniform distribution of ink is desired additional series of distributing disks can be employed, as will be obvious. Also the disks in each series may be set closer together so as to get more distributing disks in each series. The number of distributing disks employed will depend upon the size of such disks; the distance apart of such disks in each series; and the number of series of disks.

75

80

I claim:

1. In inking mechanism; the combination of a cylindrical distributing surface rotating on a fixed axis, and a plurality of series of rotatable distributing members cooperating with such surface; each series extending longitudinally thereof.

85

2. In inking mechanism; the combination of a cylindrical distributing surface rotating on a fixed axis, and a plurality of series of distributing members cooperating with such surface, each series extending longitudinally thereof, and each member rotating in a plane tangential to the distributing surface.

90

3. In inking mechanism; the combination of a cylindrical distributing surface rotating on a fixed axis, and a plurality of series of rotatable distributing members cooperating with such surface, each series extending longitudinally thereof, and the members in one series alternating with the members in the adjacent series.

95

4. In inking mechanism; the combination of a cylindrical distributing surface rotating on a fixed axis, a plurality of series of distributing members cooperating with such surface, each series extending longitudinally thereof, each member rotating in a plane tangential to the distributing surface, and the members in one series alternating with the members in the adjacent series.

100

5. In ink distributing mechanism for the purpose specified; a cylindrical distributing surface rotating on a fixed axis, a plurality of parallel series of rotatable distributing members arranged at a tangent to said surface and co-acting therewith, said series extending longitudinally of the surface, and said members rotating in a plane tangential to the distributing surface.

105

6. In ink distributing mechanism for the purpose specified; a cylindrical distributing surface rotating on a fixed axis, a plurality of parallel series of rotatable distributing members arranged at a tangent to said surface and co-acting therewith, said series extending longitudinally of the surface and said members rotating in a plane tangential to the distributing surface and the members

110

115

120

125

130

in one series alternating with the members in the adjacent series.

5 7. In inking mechanism; the combination of a cylindrical distributing surface rotating on a fixed axis, a plurality of distributing members cooperating with such surface and rotating in a plane tangential to the distributing surface, with means for yieldingly holding such members in contact with the 10 surface.

15 8. In ink distributing mechanism for the purpose specified; a cylindrical distributing surface rotating on a fixed axis, a plurality of distributing members arranged at a tangent to said surface and co-acting therewith, 15

10 said members rotating in a plane tangential to the distributing surface; with means for yieldingly holding such members in contact with the surface.

20 9. In inking mechanism; the combination of a cylindrical distributing surface rotating on a fixed axis, and a plurality of series of rotatable distributing members co-operating with such surface; each series extending longitudinally thereof, with means for yieldingly holding such members in contact with the surface.

25 10. In inking mechanism; the combination of a cylindrical distributing surface rotating on a fixed axis, and a plurality of series of distributing members cooperating with such surface, each series extending longitudinally thereof, and each member rotating in a plane tangential to the distributing 30 surface, with means for yieldingly holding such members in contact with the surface.

35 11. In ink distributing mechanism for the purpose specified; a distributing drum; and a plurality of series of distributing disks each arranged at a tangent to said drum and co-acting therewith.

40 12. In ink distributing mechanism for the purpose specified; a distributing drum; a plurality of parallel series of distributing disks arranged at a tangent to said drum and co-acting therewith; the disks in one series alternating with the disks in the adjacent series.

45 13. In inking mechanism, the combination of a distributing surface, a series of distributing disks cooperating with such surface, and means for rotating the disks, with means for yieldingly holding such disks in contact with the surface.

50 14. In ink distributing mechanism for the purpose specified; a distributing drum; a plurality of distributing disks arranged at a tangent to said drum and co-acting therewith; and means for rotating the disks, with means for yieldingly holding such disks in contact with the drum.

55 15. In ink distributing mechanism for the purpose specified; a distributing drum; and

a plurality of series of distributing disks 65 each arranged at a tangent to said drum and co-acting therewith; with means for yieldingly holding such disks in contact with the drum.

16. In ink distributing mechanism for the purpose specified; a distributing drum rotating on a fixed axis; a plurality of parallel series of distributing disks arranged at a tangent to said drum and co-acting therewith; the disks in one series alternating 70 75 with the disks in the adjacent series; with means for yieldingly holding such disks in contact with the drum.

17. In ink distributing mechanism for the purpose specified; a distributing drum rotating on a fixed axis; a plurality of series of rotatable distributing disks arranged at a tangent to said drum and co-acting therewith; said disks rotating in a plane tangential 80 85 to the surface of the drum.

18. In ink distributing mechanism for the purpose specified; a distributing drum rotating on a fixed axis; a plurality of parallel series of distributing disks arranged at a tangent to said drum and co-acting therewith, said disks rotating in a plane tangential 90 to the surface of the drum.

19. In combination, a rotatable drum, a plurality of series of distributing disks rotating in a plane tangential to the surface 95 of the drum, said disks being inclined tangentially to the drum so that only a portion contacts therewith; and means for rotating said disks.

20. In combination, a rotatable drum, a 100 plurality of parallel series of distributing disks rotating in a plane tangential to the surface of the drum, said disks being inclined tangentially to the drum so that only a portion contacts therewith, and the disks 105 in one series alternating with the disks in adjacent series.

21. In combination, a rotatable drum, a plurality of series of distributing disks rotating in a plane tangential to the surface 110 of the drum, said disks being inclined tangentially to the drum so that only a portion contacts therewith; and means for rotating said disks; with means for yieldingly holding the disks in contact with the drum.

22. In combination, a fixed rotatable drum, a plurality of parallel series of distributing disks rotating in a plane tangential to the surface of the drum, said disks being inclined tangentially to the drum so that only a portion contacts therewith, and the disks in one series alternating with the disks in adjacent series; with means for yieldingly holding the disks in contact with the drum.

23. In ink distributing apparatus, a distributing member comprising a fixed rotatable head, an annular distributing por-

- tion, and a means for clamping the annular portion on the head.
24. In ink distributing apparatus, a distributing member comprising a fixed rotatable head, an annular portion of distributing material, and a nut clamping the annular portion on the head.
25. In ink distributing mechanism, the combination of a fixed spindle having an ink distributing disk on one end, bearings for said spindle, a spring in one of the bearings for projecting the spindle, and a bushing engaging the bearing for regulating the pressure of the spring, substantially as described.
26. In inking mechanism; the combination of a cylindrical rotatable distributing surface and a series of distributing members cooperating with such surface and rotating in a plane tangential to the distributing surface.
27. In ink distributing mechanism for the purpose specified; a rotatable cylindrical distributing surface and a series of distributing members extending longitudinally of the distributing surface and arranged at a tangent to said surface and co-acting therewith, said members rotating in a plane tangential to the distributing surface.
28. In inking mechanism; the combination of a rotatable cylindrical distributing surface, a plurality of distributing members extending longitudinally of the distributing surface and cooperating with such surface and rotating in a plane tangential to the distributing surface.
29. In ink distributing mechanism for the purpose specified; a rotatable cylindrical distributing surface, a plurality of series of distributing members extending longitudinally of the distributing surface and arranged at a tangent to said surface and co-acting therewith, said members rotating in a plane tangential to the distributing surface.
30. In inking mechanism; the combination of a rotatable cylindrical distributing surface and a plurality of distributing members cooperating with such surface and rotating in a plane tangential to the distributing surface.
31. In ink distributing mechanism for the purpose specified; a rotatable cylindrical distributing surface and a series of distributing members extending longitudinally of the said surface and arranged at a tangent thereto and co-acting therewith, said members rotating in a plane tangential to the distributing surface; with means for yieldingly holding such members in contact with the surface.
32. In inking mechanism, the combination of a cylindrical distributing surface rotating on a fixed axis, a series of distributing disks extending longitudinally of the said surface and cooperating with such surface, and means for rotating the disks.
33. In ink distributing mechanism for the purpose specified; a distributing drum rotating on a fixed axis, a plurality of distributing disks extending longitudinally of the said surface and arranged at a tangent to said drum and co-acting therewith; and means for rotating the disks.
34. In ink distributing mechanism for the purpose specified; a distributing drum; a plurality of distributing disks extending longitudinally of the said surface and arranged at a tangent to said drum and co-acting therewith; and means for rotating said disks.

In testimony that I claim the foregoing as my own, I affix my signature.

ISAAC C. SQUIER.
